UNITED STATES PATENT OFFICE.

VERNON W. MILLER AND LAWSON E. MILLER, OF BRICE, OHIO.

MEANS FOR ILLUMINATING AIRPORTS.

Application filed November 28, 1927. Serial No. 235,324.

Air ports or landing fields for flying machines require illumination at night. Because air ports are large the expense of keeping them continuously illuminated at night would be large, hence the object of the present invention is to provide means whereby the aviator can, while in flight, bring about the illumination of the field preparatory to landing and also bring about the extinguishment of the light or lights while departing from the field.

According to the invention there is employed a large hopper adapted to catch a ball or other suitable object dropped or thrown by the aviator while in flight, said ball adapted to actuate a switch that will close the light circuit when desiring to make a landing, or to open said circuit and cut out the lights after a landing and in flight from the field. According to the invention also the hopper itself will be permanently illuminated at night so as to guide the aviator as to the dropping or casting the circuit actuating member when approaching the field with the purpose of landing. A further feature is the provision of a construction the operation of which will not ordinarily be interfered with or impaired by snow or rain. Other objects will appear from the disclosure herein.

The invention is embodied in the example herein shown and described the features of novelty being finally claimed.

In the accompanying drawing—

Figure 1 is a diagrammatic view of a landing field equipped with the invention.

Fig. 2 is a detail view, partly in section, and on a larger scale of the ball-receiving means and the means actuated by the ball.

Fig. 3 is a detail in side view on a larger scale of the circuit closing and opening devices.

Fig. 4 is a detail on a larger scale of the means for protecting the hopper outlet.

In the views 10 designates the hopper which is shown generally as of inverted pyramidal form. Said hopper can be made of galvanized iron wire mesh or other open work material so as to let the snow or rain pass readily therethrough. The top of the hopper (or base of the pyramid) is open so that a ball may be tossed into it and the lower end (or apex of the pyramid) is provided with a tube 11 into which the ball can roll by gravity from the wall of the

hopper and discharge into a box 12. The hopper can be supported on suitable posts 7 set in the ground, said posts being held in erect position by stays 6 to be anchored in the ground.

Pivoted upon a shaft 13 in a suitable standard 9 is a lever 14 the free slightly cupped end of which is extended into the tube 11 through a slot 15 therein, said lever carrying pivoted to it a pawl 16. Journalized loosely on the shaft 13 is a ratchet wheel 17 carrying a switch arm 18 adapted to close an electric circuit through wire 19^a when moved onto one of four contacts or terminals 19 placed ninety degrees apart on the margin of a stationary disk 20. The teeth of the ratchet wheel are so placed and the movement of the lever so limited that an oscillation downward of the lever 14 caused by the weight of the ball in the tube, will effect a forty-five degree movement of the switch arm 18. Successive operations of the lever will therefore cause the alternate closing and opening of the circuit. A spring 21 is shown as employed to restore the end of the lever 14 to its elevated position within the tube where the weight of the ball will perform the described operation. When the lever 14 is thrown down as far as it can go the ball passes on through the lower end of the tube into a box 12. Such details of equipment as may be needed and are not illustrated can be readily supplied by mechanical or electrical engineering skill.

To project the electric switching mechanism from snow and rain it is suitably covered as by a hood 23.

The rim of the upper end of the hopper is provided with a series of lamps protected from fracture by wire cages 24. These lamps can be of different colors to make the hopper clearly distinguishable from above at night; and the energizing circuit for these lamps can be distinct from the field lighting circuit so that they can be left lighted all night. The rim of the hopper is also provided with an inwardly bent margin, as at 10^a, to prevent an otherwise possible escape of a ball tending to bounce upward from points near the rim. To prevent the ball from bounding out of the hopper at other points two series of baffles or curtains of chicken wire netting 26 or other material can be hung from cross wires 27, 28, subtending the mouth of the hopper.

The air port or landing field is provided around its boundaries with a suitable number of electrical lamps 29 and a flood light lamp 30 preferably connected in multiple with a suitable source of current, the lighting circuit for these lamps being controlled by the switch arm 18, hence the aviator by dropping or throwing a ball into the hopper 10 can either turn on said lights or extinguish them according to the then position of said switch arm 18. In practice the aviator will drop the ball while in flight to turn on the lights when he arrives at a suitable point near the port; and it should be made his duty to extinguish them when he leaves the field which last he can do by dropping a ball into the hopper after he makes his take off. If the aviator is to remain in port he can extinguish the field lighting lamps by manually operating the lever 14.

To protect the upper end of the tube 10 from the collection of snow there is provided a hood 32 supported by legs a suitable distance above said end, said hood consisting of a conical or pyramidal member having an upstanding rim around its base, said rim being perforated at 33 to drain it of water when the snow melts. The hood 32 is covered with a conical screen 34 secured to the flange adapted to prevent the ball from lodging in said hood 32 and to divert the ball to the inclined wall of the hopper 10 from which it can fall into the tube or spout. The switch actuating ball, shown at 35 should, of course, be of such size as not to pass through the mesh of the hopper and of such weight as not to be seriously diverted by the wind in falling.

The forms and size of the elements can be changed without departing from the gist of the invention as claimed.

We claim:

1. Means for illuminating an air port including a field lighting circuit, a hopper into which an object can be dropped by the aviator in flight and means adapted to be

actuated by said object to close the field lighting electric circuit.

2. Means for illuminating an air port including, a field lighting circuit, a hopper into which an object can be dropped by the aviator in flight and means adapted to be actuated by said object to open or close the field lighting electric circuit. 50

3. Means for illuminating an air port including a field lighting circuit, a hopper into which an object can be dropped by the aviator to close the field lighting circuit, said hopper having open-work walls. 55

4. Means for illuminating an air port including a field lighting circuit, a hopper into which an object can be dropped by the aviator in flight to close the field lighting circuit, said hopper having inclined walls and baffle members hung within said hopper to intercept the object if bounding from a wall of the hopper. 60 65

5. Means for illuminating an air port including a field lighting circuit, a hopper into which an object can be dropped by the aviator in flight to close the field lighting circuit, said hopper having its rim inwardly deflected. 70

6. Means for illuminating an air port including a field lighting circuit, a hopper into which an object can be dropped by the aviator in flight to close the field lighting circuit, said hopper having illuminating means independent of the field lighting means. 75

7. Means for illuminating an air port including a field lighting circuit, a hopper into which an object can be dropped by the aviator in flight to close the field lighting circuit, said hopper having an outlet for said object at its bottom, and means protecting said outlet from snow and the like consisting of a hood surmounted with a flaring screen adapted to direct the falling object to a wall of the hopper. 80 85
